VALVE LENGTH TOLERANCE MEASURING ATTACHMENT FOR VALVE STEM GRINDERS

Ernest E. Heath, San Diego, and Cecil Y. Hearn, El Cajon, Calif., assignors to Bay Shore Motors, San Diego, Calif., a corporation of California

Application October 8, 1948, Serial No. 53,568

5 Claims. (Cl. 51—165)

1

Our invention relates to a valve length tolerance measuring attachment for valve stem grinders, and the objects of our invention are:

First, to provide a measuring attachment of this class which greatly facilitates the grinding of valve stems to a length tolerance after the valves have been faced, whereby precise tappet clearance of each individual valve may be readily and easily accomplished in a minimum of time.

Second, to provide a valve length tolerance measuring attachment of this class which operates in connection with a conventional valve stem grinder and which eliminates the error normally prevalent in the wearing condition of a grinding wheel during the feeding of a valve stem into the wheel a certain linear distance along the axis of the valve stem.

Third, to provide a measuring attachment of this class which permits alternate grinding and measuring operations to be accomplished without removing the valve stem from the conventional valve stem grinder cross feed mechanism.

Fourth, to provide a measuring attachment of this class which is very readily and easily set up for various valves of various sizes.

Fifth, to provide a measuring attachment of this class which may be readily and easily connected to conventional valve stem grinding machines.

Sixth, to provide a measuring attachment of this class which promotes extreme accuracy and uniformity in the valve length tolerance measuring operations.

Seventh, to provide a measuring attachment of this class which may be zeroed to fit a gage adjusted to a particular tappet and corresponding valve seat whereby the corresponding valve may be finished to a clearance tolerance substantially shorter than the gage by visual inspection of a dial indicator which registers in units of one thousandth of an inch which may be alternately employed intermediate length facing operations on the valve stem being fitted, and

Eighth, to provide a valve length tolerance measuring attachment for valve stem grinders of this class which is very simple and economical of construction, efficient in operation and which will not readily deteriorate or get out of order.

With these and other objects in view as will appear hereinafter, our invention consists of certain novel features of construction, combination and arrangement of parts and portions, as will be hereinafter described in detail and particularly set forth in the appended claims, reference being had to the accompanying drawing

2

and to the characters of reference thereon forming a part of this application in which: Figure 1 is a top or plan view of our valve length tolerance measuring attachment for valve stem grinders, showing by dash lines, the relative position of a valve stem grinder wheel and cross feed table. Figure 2 is an enlarged sectional view taken from the line 2—2 of Fig. 1. Figure 3 is a side elevational view of our valve length tolerance measuring attachment for valve stem grinders taken substantially 90 degrees to the structure shown in Fig. 1 illustrating by dash lines a portion of a valve grinder to which it is connected, and Figure 4 is a side elevational view of our valve length tolerance measuring attachment for valve stem grinders taken from the line 4—4 of Figure 3.

Similar characters of reference refer to similar parts and portions throughout the several views of the drawings.

The grinding wheel 1, carriage 2, valve stem clamp 3, valve face stop 4, measuring transfer plunger 5, spring 6, dial gage 7, screws 8 and 9, and bracket 10 constitute the principal parts and portions of our valve length tolerance measuring attachment for valve stem grinders.

The grinding wheel 1, carriage 2, valve stem clamp 3, and the valve face stop 4 are all conventional parts of a conventional valve stem grinder. The bracket 10 is a substantially rectangular block having a hollow screw 9 extending therethrough and threaded into the carriage 2, all as shown best in Fig. 3 of the drawings. The screw 8 extends through the hollow screw 9 and is adapted to engage the stem of the valve stop 4 as shown by dash lines in Figures 1 and 3 of the drawings. This bracket 10 is provided with a bore 10a therethrough in which the measuring transfer plunger 5 is reciprocally mounted. Around the stem of this plunger 5 is a coil spring 6 which abuts the head 5a of the plunger 5 tending to force the contact plate 5b of said plunger toward the bracket 10. This contact plate 5b is provided with a stop pin 5c thereon and a substantially triangular cut out portion 5d adapted to permit projection of the valve stem C into the plane of the grinding wheel 1. The dial gauge 7 is a conventional micrometer dial gauge having a reciprocating plunger 7a which contacts the plunger plate 5b and this dial gauge 7 is provided with a resetting means 10b which may be used for zeroing the indicator at a certain location assumed by the plate 5b when corresponding with a plug gauge used for measuring the distance between a valve seat and a tappet. It will be noted that the spacer 5e sur-

rounding the shank of the plunger 5 is adapted to maintain the plate 5b in spaced relationship to the bracket 10 when disengaged from the end of the valve stem C permitting the same to be passed at the cutting surface of the grinding wheel 1.

The operation of our valve length tolerance measuring attachment for valve stem grinders is substantially as follows.

A conventional gauge substantially the shape of the valve stem C is first inserted in the valve port of an engine and the distance between the valve seat in the engine block and the respective tappet is measured whereupon the length of the gauge is fixed and the gauge is then placed in connection with the carriage 2 of the conventional valve grinding machine and is held by the valve stem clamp 3 with the corresponding face portion of the gauge contacting the valve face stop 4. The plunger plate 5b is then placed in the dash line position D as shown in Fig. 1 of the drawings, contacting the end of the gauge and the dial indicator 7 by means of the recess knob 10b is adjusted to zero whereupon the valve corresponding to the respective port face and tappet measured replaces the gauge in connection with the carriage 2 and clamp 3. The face of the valve being recently finished is engaged with the valve face stop 4. A reading on the dial gauge will then indicate the surplus length of the valve stem and the operator may then grasp knob 5a of the plunger 5 and rotate the plate 5b to the notch 5d so that it will pass the end of the valve stem C longitudinally thereof and recede to the solid line position as shown in Figure 1 of the drawings under compressive force of the spring 6, thus the stem C as shown in Figure 4 of the drawings projects beyond the plate 5b permitting the same to be cut on the surface of the grinding wheel 1, it being noted that the carriage 2 is movable in the directions as indicated by the arrows A and B in Figure 1 of the drawings, and this carriage is provided with micrometer adjustments so that the operator can precisely feed the valve into the grinding wheel. After an approximate cut is made, the plate 5b is again placed in the dash line position D whereupon it is followed by the plunger 7a of the dial indicator which will indicate a substantially shorter length of the valve stem C which should bring the reading back to substantially zero as shown in Fig. 1 of the drawings, or the reading may be minus tolerance of the measurement of the gauge for proper clearance of the stem as desired, thus precise measurement of the length of the valve from the face to the end of the stem may be made with each cut on the wheel 1 until the valve stem C is substantially shorter than the setting of the gauge so that tappet clearance will be proper for the respective valve port face and tappet.

Though we have shown and described a particular construction, combination and arrangement of parts and portions, we do not wish to be limited to this particular construction, combination and arrangement, but desire to include in the scope of our invention, the construction, combination and arrangement substantially as set forth in the appended claims.

Having thus described our invention, what we claim as new and desire to secure by Letters Patent is:

1. In a valve length tolerance measuring attachment for valve stem grinders, the com-

bination with, a grinding wheel, a conventional compound carriage, movable relatively thereto, of a bracket on said carriage, a dial gauge provided with a plunger on said bracket, a plunger reciprocally mounted in said carriage having a plate thereon engageable with the plunger of said dial gauge, a clamp on said carriage adapted to hold a valve stem, a valve face stop in connection with said carriage for contacting the face of a valve, said plate having an opening therein adapted to by-pass the tappet end of said valve longitudinally thereof.

2. In a valve length tolerance measuring attachment for valve stem grinders, the combination with, a grinding wheel, a conventional compound carriage, movable relatively thereto, of a bracket on said carriage, a dial provided with a plunger gauge on said bracket, a plunger reciprocally mounted in said carriage having a plate thereon engageable with the plunger of said dial gauge, a clamp on said carriage adapted to hold a valve stem, a valve face stop in connection with said carriage for contacting the face of a valve, said plate having an opening therein adapted to by-pass the tappet end of said valve longitudinally thereof, and a spring for forcing said plate toward said dial indicator for deflecting the plunger thereof.

3. In a measuring attachment for valve stem grinders of the class described, a valve stem clamp, a carriage on which said clamp is positioned, a valve face stop in connection with said carriage, a plunger having a plate thereon provided with a cut out portion adapted to by-pass said valve stem longitudinally thereof, a dial gauge operatively connected with said plate.

4. In a measuring attachment for valve stem grinders of the class described, a valve stem clamp, a carriage on which said clamp is positioned, a valve face stop in connection with said carriage, a plunger having a plate thereon provided with a cut out portion adapted to by-pass said valve stem longitudinally thereof, a dial gauge operatively connected with said plate, a spring tending to force said plate into engagement with the end of a valve in said clamp and into engagement with said dial indicator.

5. In a measuring attachment for valve stem grinders of the class described, a valve stem clamp, a carriage on which said clamp is positioned, a valve face stop in connection with said carriage, a plunger having a plate thereon provided with a cut out portion adapted to by-pass said valve stem longitudinally thereof, a dial gauge operatively connected with said plate, a spring tending to force said plate into engagement with the end of a valve in said clamp and into engagement with said dial indicator, a stop pin in connection with said plate engageable with the stem of a valve when said plate is rotated past said cut away portion about the axis of said plunger.
